UNITED STATES PATENT OFFICE

JOHN GELOSO, OF BROOKLYN, NEW YORK, ASSIGNOR TO PILOT RADIO & TUBE CORPORATION, OF BROOKLYN, NEW YORK, A CORPORATION OF DELAWARE

DESIGN FOR AN ESCUTCHEON PLATE

Application filed September 27, 1929. Serial No. 32,890. Term of patent 3½ years.

To all whom it may concern:

Be it known that I, JOHN GELOSO, a citizen of the Kingdom of Italy, residing in the borough of Brooklyn, in the county of Kings, city and State of New York, have invented a new, original, and ornamental Design for an Escutcheon Plate, of which the following is a specification, reference being had to the accompanying drawing, forming part thereof.

Figure 1 is a plan view of an escutcheon plate showing my new design.

Figure 2 is a side elevation through lines 2—2 of Figure 1.

I claim:

The ornamental design for an escutcheon plate, as shown.

JOHN GELOSO.
